UNITED STATES PATENT OFFICE.

ANDREW HULLINGER, OF JEWETT, OHIO.

WRENCH.

SPECIFICATION forming part of Letters Patent No. 597,081, dated January 11, 1898.

Application filed May 7, 1897. Serial No. 635,575. (No model.)

To all whom it may concern:

Be it known that I, ANDREW HULLINGER, a citizen of the United States, residing at Jewett, in the county of Harrison and State of Ohio, have invented a new and useful Wrench, of which the following is a specification.

The invention relates to improvements in wrenches.

The object of the present invention is to improve the construction of ratchet-wrenches and to provide a simple and inexpensive one adapted to be readily reversed to enable a nut to be screwed on or off a bolt and capable of convenient adjustment to adapt the clamping bars or jaws to the size of the nut or part to be gripped.

The invention consists in the construction and novel combination and arrangement of parts, as hereinafter fully described, illustrated in the accompanying drawings, and pointed out in the claims hereto appended.

In the drawings, Figure 1 is a plan view of a ratchet-wrench constructed in accordance with this invention. Fig. 2 is a longitudinal sectional view on line 2 2 of Fig. 1. Fig. 3 is a similar view taken on line 3 3 of Fig. 2. Fig. 4 is a detail perspective view of the clamping-jaws and the adjusting-screws, showing the gearing for connecting the latter.

Like numerals of reference designate corresponding parts in the several figures of the drawings.

1 designates a shank or stock constituting a handle and provided at one end with a circular head or ring 2, receiving a rotary hub or casing 3, which carries a pair of adjustable clamping bars or jaws 4. The rotary hub or casing which forms a housing for the jaws or clamping-bars and the means for adjusting the same is composed of two sections 5 and 6, and the section 6 is provided with an annular series of ratchet-teeth 7, forming a ratchet-wheel and adapted to be engaged by a pair of oppositely-extending spring-actuated pawls or dogs 8, mounted on the handle or stock adjacent to the circular head or ring and adapted to engage the ratchet-wheel alternately, whereby the casing or hub may be rotated in either direction to screw or unscrew a nut. The sections of the casing or hub are detachably connected by screws 9 or other suitable fastening devices, which enable the

clamping bars and the adjusting devices to be readily inspected.

The oppositely-extending dogs or pawls 8 are held in engagement with the ratchet-wheel by their springs, and one or the other is maintained out of engagement by a cam 10, journaled in a recess of the handle or stock and provided with an exterior handle 11, which enables the cam to force either of the dogs or pawls back from the ratchet-wheel and permit the other to spring into engagement with the same. The recess which receives the pawls and the cam is covered by a suitable face-plate 12, which is provided with an opening to receive one end or journal of the cam, which is disposed between the pawls or dogs.

The sections of the casing are provided at opposite sides of the wrench with openings 13 and are recessed at their inner faces to receive the clamping bars or jaws 4, which are mounted on parallel adjusting-screws 14, journaled in suitable bearings of the casing or hub at the ends of the recesses of the sections and provided with right and left hand threaded portions, which engage correspondingly-threaded openings of the ends of the clamping bars or jaws 4.

The adjusting-screws have keyed to them sprocket-pinions 15, which are connected by a sprocket-chain 16, and one of the adjusting-screws is provided with a flattened extension 17, terminating short of the periphery of the rotary casing or hub.

The adjusting-screw which is provided with the extension 17 is adapted to be engaged by a longitudinally-movable shaft or stem 18, mounted in a bore or opening of the stock or handle and adapted to engage the said adjusting-screw when the parts are properly positioned, the casing being designed to be provided with a suitable index-mark 19 to facilitate the arrangement of the flattened extension 17 opposite the shaft or stem 18.

The shaft or stem 18 is provided at its inner end with a grooved head 21, adapted to receive and interlock with the extension 17 of the adjusting-screw, whereby when the shaft or stem is rotated the adjusting-screws will be simultaneously operated and will move the clamping bars or jaws to and from each other, according to the direction of rotation

of the shaft or stem. The outer end of the shaft or stem is squared and is provided with a threaded portion and receives a sectional knob 22. The inner section of the knob is provided with a rectangular opening and is arranged on the squared portion of the shaft or spindle, and the outer section is provided with a threaded opening and serves as a nut to engage the threaded portion of the shaft or spindle and secure the inner section on the same. The stock or shank is provided with a tubular extension or projection 23, which forms a portion of the bearing of the shaft or stem, and the knob, which is hollow, as shown, 15 fits over the same. It will be seen that the wrench is simple and comparatively inexpensive in construction, that it is adapted to be readily reversed to enable a nut to be rotated in either direction, and that it may be operated in small spaces where an ordinary wrench would be practically inoperative.

What I claim is—

1. In a wrench, the combination of a stock 25 provided with a head, a rotary casing journaled in the head and having an opening to receive a nut, a pair of clamping-bars mounted in the casing at the opening and adapted to engage a nut, said clamping-bars being 30 provided at their ends with threaded openings, adjusting-screws journaled in the casing and provided with right and left hand threaded portions engaging the threaded openings of the clamping-bars, gearing connecting the adjusting-screws, and means for operating the latter, substantially as described.
2. In a wrench, the combination of a stock provided with a head, a casing mounted in 40 the head and capable of rotation, a pair of clamping-bars arranged within the casing and provided with threaded openings, adjusting-screws journaled in the casing and having right and left hand threaded portions engag-

ing the threaded openings of the clamping-bars, gearing connecting the adjusting-screws, and a longitudinally-movable shaft mounted on the stock and arranged to interlock with one of the adjusting-screws when the same is brought opposite it, substantially as and for the purpose described.

3. In a wrench, the combination of a stock having a head, a rotary casing mounted on the latter, a pair of clamping-bars arranged within the casing, adjusting-screws having right and left hand threaded portions engaging the clamping-bars, one of the adjusting-screws being provided with an extension, gearing connecting the adjusting-screws, a longitudinally-movable shaft mounted on the stock and provided at one end with a grooved head to receive and interlock with the extension of the adjusting-screw, and a knob or handle arranged at the other end of the shaft, substantially as described.

4. In a wrench, the combination of a stock, a rotary casing mounted on the stock and composed of two separable sections, one of the sections being provided with ratchet-teeth, pawls mounted on the stock and adapted to engage the ratchet-wheel alternately, clamping-bars arranged within the casing, adjusting-screws engaging the clamping-bars and journaled in the casing, sprocket-pinions mounted on the screws, a sprocket-chain arranged on the pinions and connecting the screws, and a shaft mounted on the stock and adapted to interlock with one of the screws when the same is brought opposite it, substantially as described.

In testimony that I claim the foregoing as my own I have hereto affixed my signature in the presence of two witnesses.

ANDREW HULLINGER.
